YARN PACKAGE SUPPORT

Paul Banlier, Albi, France, assignor to Chimictex S.A., Geneva, Switzerland, a corporation of Switzerland

Filed May 29, 1962, Ser. No. 198,598

Claims priority, application France May 29, 1961

1 Claim. (Cl. 242—129.5)

This invention relates to supports for yarn packages or the like, and more particularly to a support which is automatically adjustable to conform to variations in the internal diameter of such package.

Numerous types of collapsible supports for yarn packages exist and these supports generally comprise elements capable of experiencing a radial displacement under the influence of inclined surfaces, springs, cams, or other mechanical means. Spool supports also exist which carry elastic sleeves which can be inflated under the influence of hydraulic means.

The object of the present invention is to provide a winding support, the periphery of which can be increased pneumatically by inflation of a hollow sheath or an elastic covering by means of compressed air. The winding support is in principle intended for the endwise unwinding of yarn packages.

The invention will be more easily understood by reference to one constructional example. It is quite evident that the invention is not restricted to this example, but also covers any modification coming within the same scope.

The constructional example is illustrated by the two accompanying figures, of which:

FIG. 1 is an elevation, partly in section, which shows a winding means with the sheath deflated; and

FIG. 2 is an elevation, partly in section, which shows the same winding means with the sheath inflated.

Both figures are sectional elevations, but with a package mounted thereon in FIG. 2.

In these two figures, there will be seen a supporting plate 1 which is recessed at the center. This plate comprises a hole 2 in the recessed portion. A union 3 is positioned in this recessed portion and comprises a profiled central hole 4 with a constriction 5 at the center. The tapered upper end 3A of this union serves as a seating for a rigid tube 6, which is longer than the package to be unwound. This tube is provided at the upper end with a plug 7 which can be solid or deformed with a hole, as shown in the figures. This plug has a flange 7A, the purpose of which will be hereinafter explained. It can in addition comprise a groove for a ring and the plug can also be replaced by a small cap.

A hollow elastic sheath 8, for example of natural or synthetic rubber, is fitted on the tube. This sheath is for example formed by the two ends of a rubber tube being folded inwardly until the edges of the folded portions are covered, and then by sticking these edges. The portions stuck together will be seen at 8A. The internal

2

wall of the sheath is formed with a hole 9 in its lower portion and this hole is positioned opposite a hole 10 in the tube 6. A known valve 11 is fitted through the holes 10 and 9 by means of washers 12 and 13 and a screw-threaded nut 14. The valve carries a flexible tube 15, passing through the constriction 5 of the union 3. This tube is connected by a threaded sleeve 16 to a union for a source of compressed air and can be closed. At the upper end, the sheath 8 is retained by the flange 7A.

In the deflated condition, the sheath 8 permits the easy fitting of a yarn package 17. On being inflated with air, this sheath is adapted to bear resiliently against the inside of the package, independently of any unevenness or irregularity on the inside thereof. It is even possible to use the winding support for conical packages. Throughout the unwinding operation, the sheath forms a cushion and maintains an internal elastic pressure, which facilitates the release of the convolutions, particularly towards the end.

The winding support, which is free from any movable mechanical parts, is of a very simple nature and inexpensive.

Although the winding support is particularly designed for endwise unwinding, a slight adaptation of the support and the union will enable the device to be modified for unwinding sideways.

What is claimed is:

A support for a yarn package having a hollow core, comprising a base plate, a rigid tubular member extending upwardly therefrom and adapted to extend through said hollow core, an annular sheath removably disposed around said tubular member, said sheath being composed of a flexible rubber-like material and having inner and outer walls joined at their edges to form a closed annular chamber therein, means including a coupling member connecting the interior of said hollow tubular member with said chamber for supplying fluid pressure to said chamber for expanding the same to cause the inner and outer walls of said sheath to contact and grip said tubular member and the interior surface of said hollow package respectively for securely holding the latter in position as the package is unwound, a fluid supply duct extending through said base plate and said tubular member to communicate with said coupling member and an end plate for said tubular member having a flange adapted to overlie the said annular sheath.
